UNITED STATES PATENT OFFICE.

CHARLES TENNANT LEE, OF BOSTON, MASSACHUSETTS, ASSIGNOR OF ONE-HALF TO THE GOULD & WATSON COMPANY, OF MASSACHUSETTS.

PACKING FOR STEAM-PIPES.

SPECIFICATION forming part of Letters Patent No. 411,384, dated September 17, 1889.

Application filed August 4, 1888. Serial No. 281,931. (No model.)

To all whom it may concern:

Be it known that I, CHARLES TENNANT LEE, of Boston, county of Suffolk, State of Massachusetts, have invented certain new and useful Improvements in Packings or Insulators for Steam-Pipes, Electrical Conductors, and the Like, of which the following is a specification, reference being had to the drawings accompanying and forming a part hereof, in which—

Figure 1 is a section showing a steam-pipe incased in my packing. Fig. 2 is a similar view showing the packing or insulator applied to electrical conductors.

The object of my invention is the production of a cheap and efficient packing or insulator which shall present great resistance to the passage of heat or electricity; and it consists in a layer or mass of comminuted mica in the form of flakes applied so as to surround the pipe or conductor and retained in place by a suitable case or boxing.

Mica is well known to be a good non-conductor, and it has been employed as such when applied in sheets to parts of electrical apparatus. A packing or insulator should, to insure the greatest degree of non-conductivity, contain numerous air-spaces throughout its mass or body. For this reason, among others, hair-felt is a good non-conductor, and is frequently used for packing steam-pipes, although it is not long-lived and requires to be frequently replaced.

Comminuted mica in flakes or scales of varying sizes exists in large quantities where sheet-mica is cut or mined, and is at present of little or no value. I employ this flake-mica, applying it as shown in the drawings, in

which *a* represents a steam-pipe, and *b* electrical conductors or wires. The mica (shown 40 at *d*) is placed around the pipe or conductors in a casing *f*, which may be of any desired shape and of any suitable material so long as it serves to retain the mica in place around the pipe or conductor. The mass of flake-45 mica incloses an immense number of air-spaces and forms an almost perfect non-conductor for heat or electricity. Such an insulating material applied in this way has many obvious advantages besides its cheapness. It is practically indestructible. When used around steam-pipes, if a leak occur it allows the water to drain off, and when dry 50 is again in good condition. It is easily removed when repairs are necessary, and may 55 be as easily replaced without the aid of special skill. Electrical wires may be threaded through a casing or conduit filled with it, as shown, Fig. 2, and thus easily pulled into 60 place. It forms a close layer or mass around the conductor, and combines the porosity or 65 numerous air-spaces of the felt packings with the great durability of mica, itself one of the best-known non-conductors.

What I claim is—

A non-conductor for heat or electricity, consisting of comminuted mica in a loose state and unincorporated with other material, and retained in position around the pipe or conductor by a suitable box or casing, substantially as shown and described.

CHARLES TENNANT LEE.
